ELECTRIC FURNACE FOR AND PROCESS OF HEATING SUBSTANCES UNIFORMLY AND AT A CONTROLLABLE TEMPERATURE IN AN ELECTRIC ARC.

1,094,381.

Specification of Letters Patent. Patented Apr. 21, 1914.

Application filed October 28, 1896. Serial No. 610,286.

To all whom it may concern:

Be it known that I, ERWIN F. von WILMOWSKY, a citizen of the United States of America, residing at the city of Boston, 5 Commonwealth of Massachusetts, have invented certain new and useful improvements in electric furnaces for and process of heating substances uniformly and at a controllable temperature in an electric arc, 10 and that the following is a description of the invention, which will enable those skilled in the art to which it appertains to make and use the same, reference being had to the different figures of the accompanying drawings, in which the same letters designate 15 identical or analogous parts.

I have found that an arc-furnace in which the materials to be heated are brought directly into the arc and exposed to its influence, has the disadvantage that where the arc happens to pass, the substances which are to be heated will volatilize and forcibly be dispersed, causing considerable loss while the particles close by are heated insufficiently, or too slowly, and,—although intense local heat is produced and much energy is used,—but little useful effect is produced in the heating chamber.

It is the object of my invention to so construct and proportion my apparatus that by suitable regulation a form of discharge may be maintained which will diffuse itself uniformly between the electrodes, producing a temperature which is controllable and—35 where desired—far lower than in electric furnaces known, and it is at the same time my aim to make the operation continuous.

My apparatus is constructed so that it gives generally a much reduced maximum 40 temperature and a far increased temperature in most parts of the heating chamber. Hereby the useful effect of the expensive electrical energy is greatly increased.

The drawing illustrates a sectional elevation of a furnace and electrical connections adapted to carry out my invention.

The furnace, A, may be constructed with a cylindrical carbon lining, a^1 , cemented to a carbon disk a^1 , to form a heating chamber and 50 one electrode, while centrally supported within this chamber is a movable carbon bar, b , which is the other electrode. Carbon bushings, a^2 , are cemented to the heating chamber

and contain carbon pencils a^3 , to conduct current to the chamber or draw an arc to 55 start the furnace. The chamber is incased with heat and electric insulating coverings a^4 , and bound together with an iron sheathing a^5 . A solenoid c is coiled around the covering a^4 , and insulated from the sheathing by an asbestos lining a^6 . At the bottom of the heating chamber a discharge spout a^7 , is located. A chute, d , of insulating material supports and guides the movable carbon bar b , and is provided with a sampling 65 opening closed by a mica cover d^1 . An inclined feeding tube e , mounted in bearings and having means to rotate it, conducts the charge to the chute d , from the fixed hopper f .

The carbon bar b , connects with one pole of the separately excited dynamo, g , the other pole being connected by switches, h , to portions of the chamber a , preferably to the carbon bushings a^2 . The solenoid is 75 connected in multiple to the furnace, with a suitable resistance, i , (in series with the solenoid) with the dynamo g .

If the furnace is empty the bar, b , may be lowered till it touches the disk a^1 , and 80 lifted to draw an arc. In a short time the chamber becomes filled with fine heated conducting matter, and current is now caused to traverse the solenoid. The arc now moves around the bar and the bar is lifted gradually, so the arc moves outwardly warming more of the surrounding space and as long as enough current can pass the arc is sustained, but as increasing resistance is encountered it is finally disrupted. Said fine 90 heated conducting matter consists of particles torn off or vaporized by the action of the electric current from the electrodes; said particles may be in solid or gaseous state and are highly conducting on account of 95 their high temperature. These conditions will be clear when an ordinary arc lamp is examined either in operation or thereafter. On the inside of the globe and at the bottom some fine carbon dust will be noticed. As 100 soon as the arc is disrupted, as mentioned before, the described method of starting is repeated until the bar is so high that the arc passes not any more to the bottom, but to the side of the chamber, because the distance is 105 less. When the arc is extinguished from this

- time it may be started by the pencils a^3 , without moving the bar b , and while restarting the solenoid current is first weakened and then strengthened. The arc or arcs are permitted to revolve long enough to highly heat the furnace, and then the current is increased in the discharge path moderately and to some extent in the solenoid, thereby causing more rapid rotation of the arcs.
- 10 This process is continued until a high temperature is attained when the increasing current which is being forced through the arcs, as it is bounded above and below by portions of the electrodes at a lower temperature than the plane of motion of the arcs and hence of greater resistance, causes the arcs to spread in their plane of motion, mingling one with another and forming a uniform disk across the furnace. When this
- 15 marked change in the discharge takes place, the rapid rotation ceases, the locally excessive temperature falls.
- When now—as an experiment—the central carbon-bar is with its lower end brought
- 20 in contact with the side of the furnace walls (making a short circuit) and quickly withdrawn to the previous central position, a peculiar phenomenon will be observed within the otherwise not affected arc-disk which
- 25 phenomenon consists in some slow-moving sharply-outlined, brightly-luminous matter (probably incandescent particles of the electrode material) passing from one electrode to the other in a spiral curve, proving absence of any quick rotating element at the
- 30 level of the lower end of the carbon bar. The arc disk has a tendency to be at the said level in case the current supply is mainly from the top of the furnace (*i. e.* in case current connection to both electrodes is made
- 35 mainly at the upper parts of the electrodes). The dependence herein referred to of the location of the electric discharge between concentric cylindrical electrode-surfaces
- 40 upon the levels of energy-supply has been more fully explained in an application Serial-Number 610285 filed Oct. 28 1896 simultaneously with the present case. The discharge current may now be varied and even
- 45 decreased considerably without interrupting the peculiar form of discharge, and the solenoid current may now fall to an inconsiderable relative value, and in fact is only needed to prevent abnormal but unavoidable
- 50 conditions from wholly interrupting the discharge. Such conditions will arise from impurities in the electrode material and by the different volatility of the particles of the charge, in case the furnace is used for
- 55 liquid or for solid charges. In this latter case the charge may be delivered through the rotating feeding tube e , to the furnace, and suitable changes of the currents can be made, as may be deemed necessary, from
- 60 watching the operation through the mica,

d^1 . The liquid or granular products of the reactions may be tapped off by the spout, a^7 , and the hot gases may pass off through the hopper, incidentally giving up their heat to the fresh charge. When more heat is

70 required, the discharge current is first increased and then if necessary the solenoid current when decreasing the heat the solenoid current is first diminished and then the discharge current.

If a residue from a previous operation covers the disk, a^1 , then the furnace may be started by drawing arcs with the pencils, a^3 , energizing the solenoid and on extinction repeating the process till the arcs are

75 maintained, and then following the above described process. When the heat is sufficient, the substances forming the residue are fused and may readily be removed.

80 With this furnace the supply of energy can be given at any desired level or levels. Which level answers best depends partly on the nature and on the distribution of the charge and on the speed of its motion, and is best determined empirically during the

85 operation of the furnace by successively moving the several switches supplying energy to the outer electrode. I have found that the operation can be influenced thereby greatly and the work when proceeding

90 irregularly can frequently be made normal again by a change of the supply level or levels. This influence is seen even with gaseous charges *i. e.* when the furnace is used to pass gases or vapors through to expose

95 the same to the electrical energy. This influence is evidently based on the greater or less effect of the current-elements within the electrodes upon the discharge; but whatever may be its cause the influence itself is

100 there and has been made use of herein. To demonstrate its existence the central carbon-bar can serve: when the supply of energy came from the top level, said bar shows evidence that the arc-disk has emanated from

105 the extreme end of the bar. And when the supply was given to the outer electrode at low levels, the appearance of the bar (*e. g.* the consumption of the surface-layer) and other evidence show that the arc-disk emanated uniformly from the lowest part of the carbon-bar for quite a distance *i. e.* that the disk had quite an appreciable thickness at the central electrode, which means that the

110 temperature was far more uniform in the

115 second case.

The above effect of the current within the electrodes on the discharge combines sometimes with the effect which a quick upward motion of hot gases or vapors has upon an

120 electric arc and drives the discharge—with disastrous results—upward on the central electrode in form of a flaming roaring rotating arc destroying the part of the furnace which holds the electrode. The fault

in such case has been that the energy was supplied at too low levels considering the speed of the gases. I have found a uniform and comparatively low temperature 5 and its control not obtainable without a cylindrical reacting space or with an abundance of fresh charge above the reacting space. The charge, therefore, should be added in a stream, not periodically in lots.

10 With reference to the partly diagrammatical character of the drawings, it will be understood that the carbon-pencils a^3 , when in use for starting arcs, receive current from the carbon-bushings, in which 15 they fit properly.

By the apparatus described herein I have discovered a new form of electric discharge which may simply be called a diffused discharge. It is markedly different from the 20 known discharges which have generally well defined outlines. For establishing a diffused discharge it is essential to have a confined heating chamber.

I have discovered that in the apparatus 25 described herein at comparatively low temperatures a diffused discharge can be maintained, though the same apparatus may be used for higher temperatures. When said 30 diffused discharge has been well established, as described in the foregoing, a homogeneous luminous disk stretches itself across the tube forming the heating chamber, marking on the two electrodes rings or 35 bands of entirely uniform and generally surprisingly moderate brightness, so far as the furnace is empty or so far as the character of the charge does not reduce the uniformity. No rotation whatever is visible in this form of discharge, and the electric 40 energy appears to stream perfectly uniformly between said rings at any given moment, not preferring at any moment a special linear part. This disk, when only a few 45 inches in diameter, is noiseless, except with alternating current, which besides requires, in order to form a disk, more amperes and more volts for the same apparatus. When 50 such disk-discharge has been formed with minimum energy (the way of doing it consists in forming a disk with more energy first and then gradually reducing the energy-supply), and the tubular electrode as well as the central electrode consists of pure 55 carbon the appearance of the discharge hardly is distinguished from the appearance immediately after the discharge has been suddenly stopped. The discharge looks as a 60 very steady and not in the least differentiated pure blue Bunsen gasflame of hardly unusual intensity. Evidently no solid matter is torn off from the electrode surfaces, as is the case in the known forms of arc dis-

65 When the disk is once formed, any increase in current will increase the luminosity

and the temperature, which latter can be regulated with precision by regulating the current-supply. When the electrode, b , is moved even considerably out of its central position, the disk is not changed thereby in 70 its appearance of uniform luminosity, and no motion in it is visible. Nor is the disk affected by solid materials constituting the charge and falling through the same to the bottom of the furnace unless the energy-supply of 75 the disk is too small for such work. The position of the disk is changed at will by lifting or lowering the central carbon electrode.

The temperature of the furnace when once 80 started is changed or regulated by changing or regulating the supply of electrical energy, and it is remarkable that this supply can be varied within wide limits and the temperature at the same time without destroying the 85 diffused character of the discharge. In consequence thereof the furnace described herein and operated so as outlined is useful for a far wider field of application than the electrical furnaces known. When the supply 90 of energy is reduced too much the diffused character of the discharge is changed into rotating arc discharge or the whole discharge is interrupted. When the magnetism is sustained and the current for the 95 disk reduced, the latter transforms at last quite suddenly into one or more quick rotating arcs, emitting a roaring noise even if the heating chamber consists of a carbon tube of less than two inches internal diameter. 100 This quick transition from utter silence of a discharge which is only moderately and perfectly uniformly luminous into one or more very bright rotating streamers of distinct outline is another striking feature 105 proving the difference between diffused discharge and rotating arc.

The furnace is particularly fit to pass 110 gases or vapors through which are to be exposed to electrolytic and electrosynthetic forces or to be heated to a certain temperature favorable to a desired reaction.

As any local overheating is avoided in this furnace the yield of the electro-chemical reaction or of the plain heat reaction for 115 which the furnace is used is greatly increased.

While I have described an apparatus having circular electrodes it is not necessary that such be used. It is only essential that 120 the shape and location of the electrode should be suited to the work to be performed and within the influence of the impressing electric and magnetic forces.

The apparatus may be operated either by 125 direct or by alternating current. When alternating currents are used the current in the solenoid and the furnace current must have the same period of alternation and the same phase. Both currents, therefore, are 130

- taken from the same current generator and the regulating rheostats are practically free of self induction *i. e.*, it is avoided to use for regulation wire coils.
- 5 To distinguish my invention more clearly from certain ways in which a solenoid has been used heretofore, it may be added that to thermally isolate an electrical heating chamber is not a matter of economy only:
- 10 When radiation is permitted the local temperature is at first directly reduced and then the conductivity is reduced which depends upon the temperature. This means that between two points within the electric discharge space a smaller current passes and less energy is transformed and so the temperature indirectly reduced by the permitted radiation. Therefore, the uniformity of temperature in different parts of the reacting space can not be approximated when by the furnace-construction or its use (too much fresh charge) an essential degree of radiation is permitted.
- 15 In the operation of this furnace it is preferable the cylindrical character of the electrodes is essentially maintained. A proper lifting of the carbon bar and handling of the switches supplying energy to the outer electrode is here required.
- 20 It has been stated in the above that there is an absence of any quick rotating element at the level of the lower end of the carbon bar. To avoid misapprehension, it must be noted that the main discharge is below said 25 level if the current supply is mainly from above as explained in the above cited, simultaneously filed application. Besides, it may be considered as a fact that the molecules of the hot gas within the actual discharge 30 space actually rotate around the central carbon-bar according to the principles of electric motors, though such rotation is visible only in the rotating arc and not in the described diffused discharge. The essential 35 difference is that the rotating arc has (radial) zones of excessive temperature alternating with such of comparatively far lower temperature. This feature also exists in 40 certain apparatus used for ozonizing air 45 wherein what is said to be a diffused discharge is maintained, though actually a streaming or radiating of electric energy is noticeable (even with currents of very high frequency), which precludes the uniformity 50 of temperature provided by the present invention. In all these matters the fundamental fact is that a gas has a tendency to conduct electricity in streamers because particles of the gas heated by the electric current 55 are better electric conductors than the rest. Said tendency can be overcome by increasing the conductivity either by heat as in electric furnaces for graphitizing carbon-rods or by vacuum as in Geisler tubes. Now, 60 the present invention gives a new means, of practical value in many industries, for overcoming said tendency, which means may be said to consist substantially in devices for spreading an electric discharge in two directions vertical to each other and vertical 65 to the current flow. The spreading in one of said two directions is done by the solenoid; the spreading in the other direction is done by suitably choosing the level of the current-supply. To give as an example 70 some figures, a furnace intended for gases and for a small scale may have an inside diameter of one-and-one-half inch with a central carbon rod of one-half inch diameter, then a current of fifteen amperes at forty-five 75 volts and a magnetic field of hundred-fifty ampere-turns will generally be sufficient to give a homogeneous diffused disk-discharge if a low temperature is desired and continuous current used. The energy of an ordinary arc-light of so-called thousand candle-power is spread herein so that it fills the space of about one-and-one-half square-inches 80 for a length of one-half inch or more dependent upon the gas-flow, the quality of 85 the electrode-material and above all upon the temperature existing at the time in the furnace.
- 90 Having thus described the nature of my invention what I claim is as follows:
- 95 1. In an electric arc furnace, the combination of concentric cylindrical electrodes suitably spaced apart, the intermediate space forming the furnace chamber, of a solenoid whose magnetic axis coincides substantially with that of said electrodes, and a regulator in electrical circuit with said solenoid, substantially as described.
- 100 2. In an electric arc furnace, the combination of concentric cylindrical electrodes suitably spaced apart, the intermediate space forming the furnace chamber, of a solenoid whose axis coincides substantially with that of said electrodes, independent regulators in electrical circuit with said electrodes and solenoid, respectively, and means for supplying energy to the outer electrode at different levels.
- 105 3. In an electric arc furnace, the combination of concentric cylindrical electrodes suitably spaced apart, the intermediate space forming the furnace chamber, of a solenoid whose magnetic axis coincides substantially with that of said electrodes, independent regulators in electrical circuit with said electrodes and solenoid, respectively, substantially as described, and means for establishing an arc between said electrodes.
- 110 4. In an electric arc furnace, the combination of concentric cylindrical electrodes suitably spaced apart, the intermediate space forming the furnace chamber, of a solenoid whose magnetic axis coincides substantially with that of said electrodes, independent regulators in electrical circuit with said electrodes and solenoid, respectively, 115 substantially as described, and means for establishing an arc between said electrodes.
- 120 5. In an electric arc furnace, the combination of concentric cylindrical electrodes suitably spaced apart, the intermediate space forming the furnace chamber, of a solenoid whose magnetic axis coincides substantially with that of said electrodes, independent regulators in electrical circuit with said electrodes and solenoid, respectively, substantially as described, and means for establishing an arc between said electrodes.
- 125 6. In an electric arc furnace, the combination of concentric cylindrical electrodes suitably spaced apart, the intermediate space forming the furnace chamber, of a solenoid whose magnetic axis coincides substantially with that of said electrodes, independent regulators in electrical circuit with said electrodes and solenoid, respectively, substantially as described, and means for establishing an arc between said electrodes.
- 130

- trodes and solenoid, respectively, means for supplying energy to the outer electrode at different levels, said means consisting of carbon pencils movable through the outer electrode toward and from the inner electrode, and means for conveying current to any one of said pencils.
5. In an electric arc furnace, the combination of concentric cylindrical electrodes suitably spaced apart, the intermediate space forming the furnace chamber, means for closing the upper and lower ends of said intermediate space, and for permitting the continuous feed of material through said space, of a solenoid whose magnetic axis coincides substantially with that of said electrodes, and independent regulators in electrical circuit with said electrodes and solenoid, respectively.
10. In an electric arc furnace, the combination of concentric cylindrical electrodes suitably spaced apart, the intermediate space forming the furnace chamber, means for adjusting said electrodes relative to each other in an axial direction, a solenoid whose magnetic axis coincides substantially with that of said electrodes, and independent regulators in electrical circuit with said electrodes and solenoid, respectively.
15. In an electric arc furnace, the combination of concentric cylindrical electrodes suitably spaced apart, the intermediate space forming the furnace chamber, the outer electrode being closed at one end, and the inner electrode being adjustable axially, of a solenoid whose magnetic axis coincides substantially with that of said electrodes, and independent regulators in electrical circuit with said electrodes and solenoid, respectively.
20. In an electric arc furnace, the combination of concentric cylindrical electrodes suitably spaced apart, the intermediate space forming the furnace chamber, of a solenoid whose magnetic axis coincides substantially with that of said electrodes, and independent regulators in electrical circuit with said electrodes and solenoid, respectively.
25. In a cylindrical electric arc-furnace groups of arc-starting devices located in different cross-sections of the furnace and provided with individual switches for the purpose of securing a uniform electrode-consumption and temperature, substantially as described.
30. In an electric furnace, the combination with an inclosed thermally insulated tubular heating chamber the walls of which constitute one of the electrodes, of a solenoid whose individual turns surround at least a portion of said heating chamber, and a second electrode extending within said chamber, the space between said electrodes constituting the reaction space of the furnace, substantially as described.
35. In an electric furnace, the combination with a heating chamber the inner walls of which constitute one of the electrodes, of a solenoid surrounding said heating chamber, a second electrode extending within said chamber, and a plurality of movable extensions of said wall electrode projecting into said chamber and accessible from the outside thereof, substantially as described.
40. In an electric furnace, the combination with a heating chamber constituting the reacting space for the charge, and suitable electrodes having their working surfaces within said heating chamber, of means for producing between said electrodes a diffused electric discharge, substantially as described.
45. In an electric furnace, the combination with a confined highly heated chamber within which is comprised the reacting space for the charge, and suitable electrodes having their working surfaces within said heating chamber, of means for producing between said electrodes a diffused electric discharge in at least a lower portion of said chamber.
50. In an electric furnace, the combination with a heating chamber constituting the reacting space for the charge, and suitable electrodes having their working surfaces within said heating chamber, of means including a solenoid, within which said heating chamber is located, for producing between said electrodes a diffused electric discharge at a comparatively low working temperature.
55. The process of electric furnace working which comprises forming in a heating chamber a diffused electric heating discharge, and passing through said discharge the substance to be acted upon, substantially as described.
60. The process of electric furnace working which comprises forming an electric arc or arcs, compelling such arc or arcs to lose distinct identity and coalesce in a diffused discharge, and then passing through said discharge the substance to be acted upon, substantially as described.
65. The process of electric furnace working which consists in forming an electric arc between opposed electrodes, and subjecting such arcs to suitable electric influences, compelling such arcs to lose distinct identity and coalesce in a diffused discharge, then passing through said discharge the substance to be heated, substantially as described.
70. The process of electric furnace working which consists in forming an electric arc or arcs between opposed electrodes, one of which electrodes inclosing the other, and subjecting such arcs to suitable electric influences, causing such arcs to lose distinct identity and coalesce in a diffused discharge, and passing through said discharge the sub-

- stance to be heated, substantially as described.
19. The process of electric furnace working which consists in forming an electric arc or arcs between electrodes, one of which electrodes has a substantially cylindrical inner surface and incloses the other electrode, subjecting such arc or arcs to suitable electro-magnetic influences and thereby causing such arc or arcs to lose distinct identity and coalesce in a diffused disk-like discharge, and passing through said discharge the substance to be heated, substantially as described.
20. In an electric furnace, the combination of a heating chamber, a solenoid, the heating chamber being in the plane of and inclosed by individual coils of the solenoid.
21. In an electric furnace, the combination of a heating chamber, means for producing an arc in said chamber, and a solenoid, the heating chamber being in the plane of and inclosed by individual coils of said solenoid.
22. In an electric furnace, the combination of a heating chamber, means for producing an arc in said chamber, and means for diffusing said arc.
23. In an electric furnace, the combination of a heating chamber, means for producing an arc in said chamber, and a solenoid surrounding said chamber, said solenoid having sufficient capacity to diffuse the arc.
24. In an electric furnace, the combination of a heating chamber, means for producing an arc in said chamber, and magnetic means for diffusing said arc.
25. In an electric furnace, the combination of a heating chamber and a solenoid, the heating chamber being inclosed within individual coils of the solenoid, and the solenoid being embedded within the walls of the heating chamber.
26. In an electric furnace, the combination of a heating chamber, means for substantially filling the cross-section of said chamber with an electric discharge, and means for passing material through said cross-section.
27. In an electric furnace, the combination of a heating chamber, means for substantially filling the cross-section of said chamber with a sheet of electricity, and means for passing material through said cross-section.
28. In an electric furnace, the combination of a heating chamber, means for substantially filling the cross-section of said chamber with a diffused electric discharge, and means for passing material through said cross-section.
29. In an electric furnace, the combination of a heating chamber, a solenoid having said chamber within its field of influence, and a source of alternating current connected with said solenoid.
30. In an electric furnace, the combination of a heating chamber, a solenoid, a portion of said heating chamber being inclosed within and in the plane of an individual coil of said solenoid, and a source of alternating current connected with said solenoid.
31. In an electric furnace, the combination of a heating chamber having two electrodes, means for making a short circuit between said electrodes, and means for diffusing the arc thus formed.
32. In an electric furnace, the combination of a hollow electrode forming a heating chamber; a second electrode, means for forming a short circuit between said electrodes, and means for diffusing the arc thus formed.
33. In an electric furnace, the combination of a hollow electrode and a second electrode, a pencil for forming a short circuit between said electrodes, and means for diffusing the arc thus formed.
34. In an electric furnace, the combination of a heating chamber, a solenoid having individual coils surrounding said heating chamber, said heating chamber being in the plane of said coils, and means for forming an arc in said heating chamber, said solenoid being of such capacity as to form a magnetic field strong enough to diffuse said arc.
35. The method of producing a diffused electric discharge, consisting in causing an arc to flow between electrodes, causing such arc to move by magnetism, and then increasing the current until a diffused discharge takes place.
36. The method of producing a diffused electric discharge, consisting in causing an arc to flow between electrodes, causing such arc to move by magnetism, then increasing the current until a diffused discharge takes place, and then decreasing the current.
37. The method of producing a diffused electric discharge, consisting in causing an arc to flow between circular electrodes, causing such arc to rotate by passing lines of magnetic force parallel to the axis of such electrodes, and then increasing the current until a diffused discharge takes place.
38. The method of producing a diffused electric discharge, consisting in causing an arc to flow between cylindrical electrodes, causing such arc to rotate by passing lines of magnetic force parallel to the axis of such electrodes, and then increasing the current until a diffused discharge takes place.
39. The method of producing a diffused electric discharge, consisting in causing an arc to flow between circular electrodes, causing such arc to rotate by passing lines of magnetic force parallel to the axis of such

electrodes, then increasing the current until a diffused discharge takes place, and then decreasing the current.

40. The method of producing a diffused 5 electric discharge, consisting in causing an arc to flow between circular electrodes, causing such arc to rotate by passing lines of magnetic force parallel to the axis of such electrodes, and then increasing both the 10 magnetism and the current until the diffused discharge takes place.

41. The method of producing a diffused 15 electric discharge, consisting in causing an arc to flow between cylindrical electrodes, causing such arc to rotate by passing lines of magnetic force parallel to the axis of such electrodes, and then increasing both the 20 magnetism and the current until a diffused discharge takes place.

20 42. The method of producing a diffused electric discharge consisting in causing an arc to flow between circular electrodes, causing such arc to rotate by passing lines of magnetic force parallel to the axis of such 25 electrodes, then increasing the current and afterward the magnetism.

43. The method of producing a diffused

electric discharge consisting in causing an arc to flow between circular electrodes, causing such arc to rotate by passing lines of 30 magnetic force parallel to the axis of such electrodes, then increasing the current and afterward the magnetism, and then decreasing the magnetism and afterward the current.

35

44. The process of electric furnace working which comprises forming in a heating chamber a diffused electric discharge.

45. The process of electric furnace working which comprises forming in a heating 40 chamber an electric arc, and increasing the volume of said arc beyond its normal volume in still air.

46. The process of electric furnace working which comprises forming in a heating 45 chamber a diffused electric discharge, and passing gases through said discharge.

In testimony whereof, I have signed my name in presence of two witnesses, this twenty-seventh day of October, 1896.

ERWIN F. von WILMOWSKY.
